UNITED STATES PATENT OFFICE.

ANDREW J. SANFORD, OF NEWARK, OHIO.

DESIGN FOR A LIGHT-SHADE.

40,473.

Specification for Design.

Patented Jan. 25, 1910.

Application filed June 21, 1909. Serial No. 503,569. Term of patent 14 years.

To all whom it may concern:

Be it known that I, ANDREW J. SANFORD, a citizen of the United States, residing at Newark, county of Licking, and State of Ohio, have invented a new, original, and ornamental Design for Light-Shades, of which the following is a specification, reference being had to the accompanying drawing, forming a part thereof.

The drawing is a perspective view of a glass shade showing my new design.

The leading features of my design consist in a shade body having a series of substantially flat faces, the upper series of faces

being at a greater flare or angle to the axis than the lower series of faces; and having between each pair of upper and lower faces a diamond shaped face, the intersecting faces thus imparting a peculiar jewel-like appearance.

I claim:

The ornamental design for a light shade, as shown and described.

ANDREW J. SANFORD.
